UNITED STATES PATENT OFFICE.

JOSEPH BERNARD KILKENNY, OF OAKLAND, CALIFORNIA.

FUSIBLE PLUG.

1,384,471.

Specification of Letters Patent. Patented July 12, 1921.

Application filed February 26, 1920. Serial No. 361,525.

To all whom it may concern:

Be it known that I, JOSEPH BERNARD KILKENNY, a citizen of the United States, residing at Oakland, in the county of Alameda and State of California, have invented certain new and useful Improvements in Fusible Plugs, of which the following is a specification.

This invention relates to a safety appliance primarily designed for instantly relieving the pressure in steam boilers at such time as the water therein becomes low and the rapid evaporating of the water by the intense heat of the fire in the fire-box endangers the exposing of the boiler-crown sheet subjecting the boiler to undue strains and in fact, injury.

The principal object of the invention is to provide a safety appliance of what is commonly termed the fusible type, and which when operated will permit the steam to escape from the boiler into the fire-box through a plurality of vent openings or ports, whereby the steam will be distributed over the fire-box area, thus instantly reducing the fire and at the same time serving as an alarm to the boiler attendant that the water in the boiler is at such a low point as to endanger the same. To provide a construction of the fusible type wherein the fusible element is capable of being readily replaced from a point within the fire-box, and also enabling the fusible element supporting shell to be inserted preferably in the crown-sheet from a point within the fire-box, and to further provide a construction whereby the ports of the fusible element shell for directing the steam flow into the fire-box may be utilized in positioning or removing the shell from the crown-sheet.

In the drawings, Figure 1 is a vertical sectional view, illustrating the preferred embodiment of my invention in position in an opening in a boiler crown sheet.

Fig. 2 is a transverse sectional view taken on the line 2—2 of Fig. 1, viewed in the direction of the arrow.

In the drawings 1 indicates a boiler crown plate or sheet of any well-known construction and through a threaded opening 1' thereof, is received the tubular shell 2 of suitable metal, the upper end of which projects a short distance beyond the inner surface of the plate or sheet 1, and under normal conditions, namely, when the boiler con-

tains water to the level above the sheet or plate 1, said shell extends thereinto and is maintained cooled thereby.

A chamber 3 is formed interiorly of the shell 2, the same terminating at the upper 60 end of the shell in a passage 4 and at the lower end of said shell in a threaded bore 5, both said passage 4 and bore 5 preferably of a diameter less than that of the interior of said chamber 3, providing an annular 65 flange 6 at the base of said chamber and a corresponding flange 7 at the upper end of said chamber. A shoulder 8 is also formed upon the interior of the chamber immediately below the flange 7. 70

The flange 6 at the base of the shell 2 is provided with the spaced vent channels 9 connecting the base of the chamber 3 with the interior of the boiler fire-box, said channels being inclined toward the outer edge 75 of the shell 2 and providing a means for the reception of a tool for facilitating the positioning of the shell within or the removal of the same from the boiler crown lathe or sheet. The channels 9 further provide a 80 means for directing the steam released from the boiler in a manner hereinafter described over a wide area of the fire, to reduce the heat thereof and also to warn the boiler attendant of the operation of the device due 85 to the water in the boiler running low.

Removably positioned within the chamber 3 of the shell 2 is a suitable plug 10 adapted when the shell is in position as in the drawing to be inserted thereinto from a point 90 within the fire-box through the opening 5. A portion of the plug extending into the chamber 3 is of a diameter approximately equal to that of the opening 5 insuring a space around that portion of the plug within 95 the channel 3, said space being insured by extending the plug centrally through the chamber and forming the chamber of a diameter larger than that of the opening 5. To facilitate the positioning and removal 100 of the plug relatively to the shell 2 said plug is preferably formed on its lower end with a wrench receiving portion 11 which falls short of overlying the lower discharge ends of the channels 9. The plug is formed longitudinally of its center with a fusible element receiving bore 12 opening at the opposite ends of the plug and from said bore, approximately midway in its length extend the laterals 13, the outer ends of which are dis- 110

posed to lie slightly above the upper surface of the flange 6 when the parts are assembled as in the drawing.

At a point immediately below the connection of the laterals 13 with the bore 12, said bore is restricted by an annular shoulder 14 and from said shoulder the upper end of said bore is preferably outwardly flared as at 15, and below said shoulder the walls of said bore are preferably parallel as illustrated.

The bore 12 and laterals 13 are filled with a suitable fusible element 16, preferably poured thereinto when the plug is removed from the shell 2. The upper end of said element projects above the upper end of the plug 10 as at 17, the projecting portion being of a diameter corresponding to that of the passage 4 and preferably of a length to lie flush with the upper surface of the shell when the plug is positioned therein, as in the drawings. The plug 10 at its upper end is of a diameter to snugly fit within the confines of the shoulder 8 and to contact with the under surface of the flange 7, said contacting portion of the plug and shell together with the snug fit of the portion 17 of the element 16 with the wall of the opening 4 prevents the escape of steam or water from the boiler into the chamber 3 until such time as the element 16 is melted, as hereinafter described.

The device when assembled as illustrated in the drawing operates in the following manner:—

On the lowering of the water level in the boiler to a point to expose the upper portion of the shell 2 the fire box heat passing through the vent ports 9 materially raises the temperature of the plug 10, over that when the shell is surrounded by water, consequently this increased temperature permits the rapid fusing of the element 16, at which time the boiler steam pressure displaces the same from the bore 12 and laterals 13 permitting the released steam pressure in the boiler to escape therefrom through said bore 12 and laterals 13. The tapering of the bore 12 as in the drawing and the providing of the flange or shoulder 14 which restricts the lower end of said bore causes the steam admitted through the upper end of the bore to be forced laterally under pressure through said laterals 13 into the chamber 3 from which it escapes in the form of jets through the relief channels 9, which direct the released steam over a wide area of the fire enabling the fire to be reduced by this steam

volume at the time when the boiler water is low and also relieving the boiler pressure. After the device is operated and it is desired to insert a new one prior to refitting the boiler, it is only necessary that the old plug be removed and a new one inserted in its place. By constructing the casing or shell side walls as in the drawing, it is possible to insert or remove the shell from the crown sheet opening from a point interiorly of the boiler fire-box.

Having thus described my invention what I claim is:

1. A safety appliance for steam boilers comprising a tubular shell communicating at one end with the boiler water space and at its opposite end with the boiler fire box, said shell provided on its interior with an enlarged chamber, relief ports connecting the shell with the boiler fire-box, a tubular plug removably positioned within said shell to close, its opposite ends, a fusible element closing the tubular portion of said plug with one end exposed to the boiler fire-box, said plug provided with lateral channels communicating with the enlarged chamber whereby the fusing of said element provides a connection between the boiler water space and the fire box through said enlarged chamber.

2. A safety appliance for steam boilers comprising a tubular shell exposed at one end to the interior of the boiler water space and at its opposite end to the boiler fire-box, said shell provided on its interior with an enlarged chamber and at one end with relief conduits connecting said chamber with the interior of the boiler fire-box, a tubular plug removably positioned within said shell for closing one end of the tubular portion thereof, the tubular portion of said plug being restricted adjacent one end and having lateral channels extended therefrom to provide communication with the shell chamber, and a fusible element positioned within said plug for closing the channel therein and the laterals thereof, the opposite ends of said fusible element being exposed one to the boiler water chamber and the other to the boiler fire-box.

In testimony whereof I have signed my name to this specification in the presence of two subscribing witnesses.

JOSEPH BERNARD KILKENNY.
